PULSE COUNTING AND CHECKING APPARATUS

Maxwell R. Cannon, Endicott, N.Y., assignor to International Business Machines Corporation, New York, N.Y., a corporation of New York

Filed June 25, 1958, Ser. No. 744,359

15 Claims. (Cl. 315—84.6)

This invention relates to gas tube counters and more particularly to checking or verification circuits employing gas tube counters.

For counting electric pulses which are emitted at a high repetition rate, it has been proposed to use multicathode gas tubes wherein a glow or other gaseous discharge is stepped along from one cathode to another in response to the reception of pulses that are being counted. While such counters have been demonstrated to be workable and efficient for rapidly storing pulse counts, they have not heretofore been regarded as satisfactory in situations where an extremely rapid, and in many cases non-destructive, read-out of the stored pulse count is needed. One such application is the checking or verification of data recorded in tabulating cards or the like. One may wish, for example, to verify serial numbers in cards which supposedly are arranged in a progressively ascending order. A progressive count against which the card numbers are to be verified is maintained in a counter, with the stored count being read out nondestructively and increased by 1 for each card verified. There is an increasing demand for verifiers having counters which can store and read out their reference numbers at a rate much higher than that of the conventional electromechanical counters now available. Prior gas tube counters have not been regarded with favor for this purpose because their read-out periods have not been sufficiently brief to warrant their substitution for electromechanical counters. Moreover, gas tube counters heretofore have not lent themselves to nondestructive read-out, except by the "roll-out" method which not only is slow but entails some risk of destroying the stored data as well.

There are several modes of verification, such as serial number verification, mentioned above, "gang" verification in which the identifying numbers of all cards in a run are checked against a stored master number that is read out nondestructively and without change, and random verification in which the stored number is read out destructively and is replaced by an unrelated number each time. Present-day conditions point toward the need for verifiers which can handle up to 10,000 cards per minute for serial or gang verification and around 4,000 cards per minute for random verification. Verifiers of prior design cannot even approach these speeds, but by using the principles of the present invention one may easily attain these high output rates.

An object of the present invention is to provide a practical gas tube counter circuit having novel read-out features which enable the stored count to be read out at the rate required in high speed operations of the magnitude indicated hereinabove.

Another object is to provide a gas tube counter circuit in which this high read-out rate may be attained without any risk of destroying the stored data, for those applications where a nondestructive read-out is required.

Still another object is to provide a high speed veri-

2

fication apparatus which is completely fail-safe in its operations.

A further object is to provide gas tube counter circuit which is adapted to operate with transistorized driving and output stages.

A still further object is to provide a fail-safe verification circuit using solid-state elements for performing all of the required error checks such as the detection of incorrect marking, double marking and failure to mark.

These and other objects will become apparent from the following detailed description of the accompanying drawings.

In the drawings:

Fig. 1 is a diagram of a counter circuit employing a gas tube counter having a nondestructive read-out constructed in accordance with this invention;

Fig. 2 is a view showing various wave forms applicable at various points in the drive circuit for the gas tube counter of Fig. 1;

Fig. 3 is a view showing a circuit diagram of the verification circuit of the present invention;

Fig. 4 is a view illustrating signal wave forms fed to the circuit of this invention when a particular card being verified is found to be correctly marked;

Fig. 5 is similar to Fig. 4 only showing a signal resulting from erroneous marking of a tabulating card;

Fig. 6 is similar to Fig. 4 only showing signal resulting from the double marking of a tabulating card;

Fig. 7 is similar to Fig. 4 only showing the signal resulting from a failure to mark a particular card;

Fig. 8 is a circuit diagram of a fail-safe trigger used in the verification circuit of this invention.

Turning to Figs. 1 and 2, which illustrate a single-order counter embodying the invention, the multicathode gas tube 10 has its anode 11 connected to a B+ source of about 400 volts. The resistor 12 may have a value of about 470K. The cathodes of the tube 10 are numbered 0 to 9, inclusive, and each is connected in parallel to the anode electrodes of two diodes, d_{01} and d_{02} , d_{11} and d_{12} , etc. Each even diode (d_{02} , d_{12} , etc.) is commonly connected by line 13 and timing bus 14 to resistor 15. Resistor 15 is connected between -20 volts and the base of inverter transistor T_1 , an NPN type. Each odd diode (d_{01} , d_{11} , etc.) is connected to succeeding outputs of a ring counter 17. The ring counter samples or "strokes" each cathode in turn by providing pulses to the various cathodes 0 to 9 successively at times respectively corresponding to the digits from "0" to "9" in the basic timing cycle of the verifying machine or other device which the counter is being employed. The ring is advanced by a suitable clock pulse generator 60 which furnishes clock pulses at a standard repetition rate as determined by the basic machine cycle or other timing period. Any other equivalent sampling or "strobing" means may be provided in lieu of the clock 60 and timing ring 17.

The tube 10 is adapted to count pulses furnished by a suitable source to represent any of the digits from "0" to "9." If the numerical count stored in the tube 10 is "5," for example, a discharge is maintained between plate 11 and cathode 5. Under these conditions the diode d_{52} is forwardly biased, and current flows through d_{52} , the timing bus 14, the line 13 and resistor 15 to the -20 volt source. Diode d_{51} is normally blocked, but when pulsed by the ring counter at digit time "5," it shunts a significant amount of the cathode current through it, thus decreasing the current flow through resistor 15. This varies the voltage at the base of transistor T_1 towards -20 volts and thereby reduces the collector current of T_1 , increases the base voltage of inverter transistor T_2 , a PNP type, and reduces the collector current through resistor 16. Therefore, by pulsing d_{51} at digit time "5,"

there is obtained a negative pulse output across resistor 16 at digit time "5."

The driving circuit for the gas tube 10 is illustrated as comprising two transistors T_3 and T_4 and associated circuitry. Other equivalent means employing vacuum tubes may be substituted; however, it is one of the objectives of the present invention to provide a counter which will use transistorized driving and output stages. To the input condenser 18 are fed pulses in a number which is a function of the correct value of the information supposedly recorded on the card or other record that is being verified. This can be done in any conventional way.

Assuming that the disclosed counter is to be employed for storing serial numbers, the initial entry into the counter may be obtained by scanning a master card containing the first number of the series. By conventional means (not shown) the digital value in each order or column of the scanner number is converted to a corresponding series of positive pulses which are fed through the input condenser 18 to transistor T_3 . Thereafter, for each card verified, a single positive pulse only is applied to transistor T_3 . It is understood, of course, that this will occur in the units order of a multiorder counter, with carryover between orders when necessary. The carryover means and the additional orders of the counter are not illustrated herein because they are not essential to an understanding of the invention and may readily be provided by a person skilled in the art.

Each positive pulse applied through condenser 18 to transistor T_3 decreases the collector current in T_3 to lower the voltage at point 20 from +20 volts to -60 volts as determined by the action of the clamping diode 21. When condenser 18 has charged, the transistor T_3 returns to its normal state and point 20 again returns to +20 volts. This provides an output pulse 22, Fig. 2, to the guide G_1 of the gas tube 10, Fig. 1. Point 23 meanwhile has made the same kind of excursion as point 20 but due to the fact that transistor T_4 is a PNP type, the positive excursion of this point provides an output at point 24 as shown by pulse 25, Fig. 2, for guide G_2 . It is necessary, for reasons explained below, that these two pulses 22 and 25 fed to the guides G_1 and G_2 of counter tube 10 be displaced somewhat in time with respect to each other.

Before counting begins, the discharge in tube 10 is between plate 11 and cathode 0. The negative pulse 22 causes the discharge to transfer to guide G_1 . The negative pulse 25 transfers the discharge to guide G_2 , and after the expiration of pulse 25 the discharge shifts to cathode 1. Further input pulses to the driving circuit will step the discharge along from cathode to cathode. When the discharge is located at a particular cathode, the voltage of that cathode rises to forward-bias its even-numbered diode. Its odd-numbered diode remains blocked until unblocked by the ring counter 17 as previously described. The output pulse from the counter, taken across resistor 16 in a time interval representative of the count stored in the tube 10, is fed to the verification circuit which is illustrated in Fig. 3. A verification circuit of this kind is provided for each column of the numbers being verified.

Suitable reset means (not shown) is provided for resetting the counter 10 to its "zero" condition. Reset of the counter tube merely involves opening the cathode circuits of the cathodes 1 to 9 and biasing cathode 0 sufficiently negative to establish the glow discharge there. During gang or serial verification the counter 10 is reset only at the end of a card run. During random verification reset occurs after each read-out, which would be a destructive read-out in each instance.

Referring to Fig. 3, pulse 26 represents the counter output obtained from transistor T_2 of Fig. 1. Pulse 27 is fed to the verification circuit from the reading brushes or scanning means which scan the tabulating card being verified. Pulses 28 are clock pulses from clock pulse

generator 60 which is synchronized with the scanning operation and which drives the ring counter 17 of Fig. 1.

The verification circuit employed in conjunction with the gas tube counter checks (1) correct marking, (2) erroneous marking, (3) double marking, and (4) blank columns in the tabulating cards being verified. Referring to Fig. 4, there is shown a typical time sequence of pulses that occur when the card is correctly marked. The brush or scanning means provides a pulse 27 at digit time "5" (t_5) showing that the card is marked or punched at digit position "5" in the particular column thereof being scanned. Assuming that the reference number stored in counter 10 is "5" for this particular card column, the gas tube counter circuit will provide a read-out pulse 26 to the verification circuit of Fig. 3 at time t_5 . The clock generator 60 (Fig. 1) provides pulses 28 at each of the digit time intervals, including time t_5 . It will now be shown that under the conditions of Fig. 4, that is with an assumed correct marking of the tabulating card, no error signal will result.

Referring to Fig. 3, an inverter 29 provides a positive pulse output to the negative AND circuit or gate 30 in response to the negative reading brush pulse 27 at time t_5 , effectively blocking this gate at time t_5 . Consequently, there is no pulse output to the OR circuit 31 on line 32. The reading brush pulse 27 is also fed along line 33 to the negative AND gate 34. The counter pulse 26 is fed to an inverter 35 along a line 36 to provide a positive pulse output on line 37 leading to the negative AND gate 34. Therefore, gate 34 is effectively blocked at time t_5 , and no pulse output is fed to the OR gate 31 along line 38.

Reviewing the above, it is seen that at time t_5 , under assumed conditions of correct marking, the input voltage on leg A of negative AND gate 30 is "up," while the input voltages on legs B and C are "down," thus blocking the negative AND gate 30. With regard to negative AND gate 34, leg A is "down" and leg B is "up," thus blocking this gate also. Consequently, no signal travels through either branch of the logical circuit to the stop trigger 43. Stop trigger 43 provides an indication of an error in the tabulating card being scanned whenever an output is obtained from the OR gate 31 and may operate means to disable the card feeding mechanism, or it may reject the erroneously punched card or perform some similar function. As long as this trigger 43 does not receive a pulse from the logical circuit, the scanning operation and verification of tabulating cards continues in normal fashion.

Fig. 5 illustrates a sequence of events due to erroneous marking of the tabulating card, it being assumed for illustration that the card has a marking thereon at digit position "4" rather than at the correct digit position "5." Referring to Fig. 3, at time t_4 the voltage on leg A of negative AND gate 34 is "down," as is that of leg B also. It should be noted that the output potential of each of the inverters 29 and 35 is normally down and only goes up when a negative input is applied to said inverter. Consequently, at time t_4 , negative AND gate 34 provides an output along line 38 to negative OR gate 31. Negative OR gate 31 provides an error signal through an emitter follower 40, a line 41 (of which there is one for each order or column of the numbers being verified), and a negative OR gate 42 to the stop trigger 43. This trigger 43 provides an indication of the erroneous marking of the tabulating card being scanned in a manner to be explained later in connection with Fig. 8.

Fig. 6 illustrates a typical problem of double marking, that is a correct marking on the card column being scanned at digit position "5" coupled with an erroneous marking thereon at digit position "7." Referring again to Fig. 3, it can be seen that at time t_6 no error signal is fed to the stop trigger 43. However, at time t_7 , negative AND gate 34 provides an error signal in a manner similar to that explained with reference to Fig. 5.

Fig. 7 illustrates what happens when there is a blank column on the card where there should be a column marked at position "5" therein. At time t_5 , under these conditions, the voltages on all of the legs, A, B and C, of the negative AND gate 30, Fig. 3, are "down," thus providing an error signal to the stop trigger 43.

Fig. 8 shows the fail-safe construction of the stop trigger 43. This trigger includes two transistors of opposite conductivity types, namely, T_5 , a PNP type, and T_6 , an NPN type. The trigger operates in a fashion such that if one transistor is conducting it will cause the other to conduct, and if one transistor is shut off it will cause the other to shut off. Let it be assumed that both transistors are reversely biased and consequently non-conducting. The application of a negative reset pulse 44 on line 51 through resistor 52 to the base of T_5 will cause T_5 to conduct. This will energize relay 46 by providing a current path from the -20 volt supply through the relay and T_5 . Approximately -20 volts will appear at the collector of T_5 . The voltage divider action between -20 volts and +10 volts through the voltage divider consisting of the resistors 47, 48 and 49 will apply a forward bias on transistor T_6 . Now both transistors are conducting. Should an error signal be supplied from the output of negative OR gate 42 through condenser 50 to the base of T_6 , T_6 then will become nonconducting. The voltage drop across resistor 45 then is such as to reverse bias the transistor T_5 also. The relay 46, having no closed current path through its winding, will become deenergized, and the circuitry controlled by relay 46 (not shown) will act accordingly. The card error signal may be manifested by shutting down the card feed, ejecting the defective card, etc. The diode 53 shunts any voltage developed inductively by the coil of the relay 46.

It can be seen that the trigger 43, if it fails, will fail in a safe manner. If the relay 46 or either or both of the transistors T_5 and T_6 should fail, the trigger 43 will operate the relay-controlled circuit to indicate an error. The same result is obtained by failure of these components of the trigger as would be obtained by the introduction of an error signal from OR gate 42. The same fail-safe result is also obtained if the gas tube counter circuit of Fig. 1 fails to provide a pulse output 26 during the "strobing" of its cathodes. This may be due to failure of any of the components of this counter circuit to function properly, even failure of the strobing means itself, namely, the ring counter 17. If the input to the verification circuit consists of the brush pulse 27 alone, it will provide an output from negative AND gate 34 to drive trigger 43 to its nonconducting state.

What has been described is a specific embodiment of the present invention. Other embodiments obvious from the teachings herein to those skilled in the art are contemplated to be within the spirit and scope of the following claims.

What is claimed is:

1. A gas tube pulse counter circuit including a multi-cathode gas discharge tube, means to advance a plate-to-cathode discharge in said tube from one cathode to another as a function of a pulse input to said circuit, and a read-out means to read out nondestructively from said tube a count stored therein, said read-out means comprising a source of potential, pairs of first and second unidirectional current conducting devices, the devices of each pair being connected at one end thereof to a respective one of said tube cathodes, means connecting all of said first devices of said pairs of devices to said source of potential whereby a discharge between a selected cathode and the plate of said tube will forwardly bias the first device of the pair of devices associated with that cathode, means to advance a forward-biasing voltage from the second device of a pair to the second device of the next succeeding pair, and means to provide a read-out

voltage upon the simultaneous forward biasing of both of the devices associated with the selected cathode.

2. A circuit as defined by claim 1 wherein the first and second unidirectional current conducting devices of each pair are diodes.

3. A circuit as defined by claim 2 wherein said connecting means includes an impedance, and said read-out voltage is developed across said impedance.

4. A circuit as defined by claim 2 wherein said means 10 to advance a forward-biasing voltage includes a sequential conditioning means providing sequential pulse outputs from the various stages thereof, and means connecting each of said second devices to a separate stage of said counter.

15 5. A circuit as defined by claim 2 wherein the plate electrode of each diode is connected to its associated cathode of said gas discharge tube.

6. A circuit as defined by claim 3 wherein the cathode electrode of each first device is connected to said impedance and the plate electrode thereof is connected to its associated cathode of said gas tube, and the cathode electrode of each second device is connected to a separate stage of said conditioning means and said plate electrode thereof is connected to its associated cathode of said gas tube.

30 7. A gas tube pulse counter circuit including a multi-cathode gas discharge tube, means to advance a plate-to-cathode discharge in said tube from one cathode to another as a function of a pulse input to said circuit, and a read-out means to read out nondestructively from said tube a count stored therein, said read-out means comprising a source of potential, means connecting all of said cathodes together, an impedance connecting said cathode connecting means to said potential source, normally nonconducting individual devices respectively associated with said cathodes, each device capable of being conditioned to provide a shunt path for the current of its cathode in the event said cathode is carrying said discharge, means for sequentially conditioning said nonconducting devices so that they become conductive in a timed sequence whereby the normally nonconducting device connected to said discharge-carrying cathode becomes conductive to decrease the cathode current flowing through said impedance at a time which is representative of the count being read out, and means to detect said current decrease as a read-out indication of said count stored in said tube.

35 8. A circuit as defined by claim 7 wherein said cathode connecting means and said normally nonconducting devices are electrically isolated from each other.

40 9. A circuit as defined in claim 7 wherein said connecting means includes a common conductor, a unidirectional current conducting device associated with each of said tube cathodes, and means to connect said devices 45 to said common conductor.

45 10. A circuit as defined by claim 7 wherein each of said normally non-conducting individual devices comprises a unidirectional current conducting device and wherein said sequential conditioning means comprises a ring counter and means to connect each of said normally non-conducting unidirectional current conducting devices to a separate stage of said counter.

50 11. A circuit as defined by claim 10 further including at least two cascaded transistorized inverters, means to feed the voltage developed across said impedance to the first of said inverters, and means to obtain an output from the last of said inverters as a read-out voltage indicative of the count in said tube.

55 12. A verification circuit for indicating the lack of positional comparison between an actual marking on a record and a correct marking thereof comprising a two-input AND gate, a three-input AND gate, a two-input OR gate, means to feed a time positional pulse indicative of said actual marking on said record to one input 60 of said two-input AND gate, means to feed an inverted

65 70 75

time positional pulse indicative of said correct marking of said record to the other input of said two-input AND gate, means to feed a time positional pulse indicative of said correct marking to one input of said three-input AND gate, means to feed an inverted time positional pulse indicative of the actual marking on said record to another input of said three-input AND gate, means to feed a train of timing pulses to the last of said inputs to said three-input AND gate, means to feed the respective outputs of said AND gates to separate inputs of said OR gate, and means to indicate a pulse output from said OR gate as an indication of said lack of comparison between said actual marking on said record and said correct marking thereof.

13. A circuit as defined by claim 12 further including a bistable trigger, said trigger normally being in one stable state, means to feed the pulse output of said OR gate to said trigger to flip said trigger to the other of its stable states, and means to indicate a change in the state of said trigger as an indication of said lack of positional comparison.

14. A circuit as defined by claim 13 wherein said bistable trigger includes two transistors of opposite conductivity types, both of said transistors being conductive in one of said stable states and non-conductive in the other of said stable states.

15. A circuit as defined by claim 12 wherein said

5

10

15

20

means to feed a time positional pulse indicative of the correct record marking comprises a gas tube pulse counter circuit including a multi-cathode gas discharge tube, means to advance a plate to cathode discharge in said tube from one cathode to another as a function of a pulse input to said circuit, and a read-out means to read out non-destructively from said tube a count stored therein, said read-out means comprising a source of potential, pairs of first and second unidirectional current conducting devices, the devices of each pair being connected at one end thereof to a respective one of said tube cathodes, means connecting all of said first devices of said pairs of devices to said source of potential, whereby a discharge between a selected cathode and the plate of said tube will forwardly bias the first device of the pair of devices associated with that cathode, means to advance a forward-biasing voltage from the second device of a pair of the second device of the next succeeding pair and means to provide a read-out voltage upon the simultaneously forward biasing of both of the devices associated with the selected cathode.
